UNITED STATES PATENT OFFICE.

ROY C. ARTER, OF GALION, OHIO, ASSIGNOR TO THE NORTH ELECTRIC MANUFACTURING COMPANY, OF GALION, OHIO, A CORPORATION OF OHIO.

MACHINE-SWITCHING TELEPHONE SYSTEM.

Application filed June 7, 1920. Serial No. 387,275.

To all whom it may concern:

Be it known that I, Roy C. Arter, a citizen of the United States, residing at Galion, in the county of Crawford and State of Ohio, have invented a certain new and useful Improvement in Machine-Switching Telephone Systems, of which the following is a specification.

This invention relates to improvements in machine switching telephone systems, and particularly in the selecting and switching circuits of machine switches.

According to one of the features of the invention, connections may be established between a line and an idle one of a plurality of lines divided into groups, by first selecting the desired group and connecting with all the lines contained therein and then disconnecting all but one idle line which is retained for the purpose of establishing a desired connection. Due to this method of selection, the so-called trunk hunting operation is obviated and a line may be instantaneously seized.

Other features of the invention have to do with party line ringing, improved test circuits, improvements in impulse control circuits and various other elements of machine switching systems, as will appear from the following description and the appended claims.

In the drawings, Fig. 1 illustrates the circuits of trunk finding and trunk selecting switches; Fig. 2, the circuits of connector switches, and Fig. 3, counting relays that co-operate in the control of connector switches.

General description of the system.

The present system is a thousand line machine switching telephone exchange system, in which connections are established under the control of calling parties. By means of a calling device of any well known design, such as that shown in the application of A. H. Adams, Serial No. 488,606, filed July 30, 1921, the calling party sends out impulses representing the hundreds, tens and units digits of the called line number and, finally, impulses for controlling the selection of ringing current of the desired frequency to ring the bell of the station wanted on the called line.

The machine switches used in the establishment of a connection are multi-contact switching relays, preferably of the type disclosed in Patent No. 1,091,193 to E. E. Clement. Three sets of relay switches are used for the establishment of connections: one set, finder relays 110 and 120, to connect the calling line with an idle one of a plurality of selector trunks; a second set, selector relays 180 and 190, for connecting the selected trunk with an idle one of a plurality of connector trunks, the hundreds designation of which corresponds to that of the called number; and a third set, connector relays 280 and 290, for connecting the selected connector trunk with the called line. Relays 110 and 120 are automatically operated upon the initiation of a call, relay 190 is operated in accordance with the hundreds digit of the called number, relay 180 is automatically operated to connect an idle trunk of the group designated by relay 190, relay 290 is operated in accordance with the tens and relay 280 in accordance with the units digit of the called number.

The relays like 110 carry the answering and the relays like 290 carry the calling terminals of lines. All the answering terminals of a line are multiplied together and with the multiplied calling terminals of the respective line. The calling and answering terminals comprise a set of three contacts through which the line and test conductors of a substation may be connected with a selector trunk like A and a connector trunk like 171—173. The number of the selector and connector trunks depends on the requirements of the traffic, all the trunks being arranged like the ones disclosed in the drawings.

Associated with the answering end of each selector trunk like A there is a multi-contact relay like 115. The contacts of this relay are divided into two groups of ten contacts. The contacts in one group represent the units digits 1—0 and the contacts in the other group the tens digits 1—0. These contacts are connected, on one hand, with the front contacts of the various line relays like 101, and, on the other hand, with the windings of the various relays like 110 and 120 associated with the answering end of the respective trunk. The connection with the line

relay contacts is in accordance with the tens and units numerical designation of the respective line, and the contacts of each line relay are multiplied to the contacts of as many relays like 115 as there are trunks to which the line should have access upon the initiation of a call.

One switching relay like 110 is associated with the answering end of each selector 10 trunk to connect it with a certain group of ten subscribers' lines, each relay carrying 31 contacts, thirty of which are in ten sets of three, one set individual to each line. There are ten relays like 120 associated with 15 the answering end of each selector trunk. The tens contacts of a relay 115 are connected in numerical order to the windings of the various relays 110, and in a similar manner the units contacts of a relay 115 are connected to the windings of the various relays 20 120 associated with the answering end of the respective selector trunk.

Upon the initiation of a call, if the trunk A is idle, the relay 115 is actuated, and depending 25 on the identity of the calling line, a certain pair of line finder relays like 110 and 120 are operated to connect the line with the trunk. If the trunk A is busy, then the relay 104 is in actuated condition, and the initiation of the call results in the operation 30 of a relay 115^b associated with the next idle selector trunk. This relay causes then the extension of the calling line to the last mentioned trunk. The relay 104^b, associated 35 with this trunk, may similarly extend the call to the succeeding selector trunk, etc. While a selector trunk is being selected, a relay 103, associated therewith, is maintained energized to prevent the initiation of 40 calls within the group of lines having access to the mentioned trunks. It should be noted in this connection that instead of the specific circuit arrangement herein disclosed, various arrangements, e. g., like the one 45 shown in Patent No. 1,252,974 to H. G. Webster, may be employed for controlling the operation of switching relays without departing from the spirit of the present invention.

Associated with each selector trunk, there 50 is a set of counting relays 131—140. One pair of counting relays is provided for each of the digits 1—0, only three pairs of relays being illustrated in the drawings. The left-hand outer contacts of relays 131'—140' lead to the first, second, etc., hundreds selector relays 190, 190^a, etc. These counting relays are operated by the calling party sending 55 current impulses representing the hundreds digit of the called number. In accordance with the operation of the counting relays, a certain one of ten hundreds-selecting relays (190, 190^a, etc.) is actuated. The contacts of these selector relays are connected 60 to connector trunks like 171—173,

174—176. The relay 190 represents the hundreds digit "2," and the trunk conductors 171—173 are multiplied to the contacts of a plurality of relays representing this digit and associated with the various selector 70 trunks. The connector trunks connected to the contacts of the relay 190 all serve for giving access to subscribers' lines, the hundreds designation of which is "2." Depending 75 on the idle or busy condition of the connector trunks terminating in the contacts of the actuated relay 190, a certain one of the trunk selecting relays 180—180^b is actuated. These trunk selecting relays are also associated with the calling end of the selector 80 trunk, the number of such trunk selecting relays associated with a trunk being determined by the number of connector trunks to which a selector relay has access. The trunk selecting relays operate to connect the 85 calling end of the selector trunk with a selected connector trunk through any one of the hundreds-selector relays actuated under the control of the counting relays.

A set of counting relays 301—310 is associated 90 with each connector trunk. These counting relays are operated in accordance with the tens, units and stations impulses. The bottom contacts of relays 301'—310' are connected in multiple to the first, second, etc., tenth contacts of relays 275, 285 and 295. Under the joint control of the counting relays and relays 322 and 295, a tens connector relay like 290 is actuated. This connector relay represents the tens digit of 95 the called line, ten such relays representing the various tens digits being associated with the calling end of each connector trunk. Each subscriber's line is multiplied to the contacts of a plurality of tens connector relays 100 representing the designation of the line. The relay 295 is provided in common to all the tens connector relays of a connector trunk.

Under the control of the counting relays, 110 operated in accordance with the units impulses, and relays 324 and 285, a units connector relay like 280 is operated. The calling end of each connector trunk is provided with ten units connector relays representing 115 the various units digits, the contacts of these relays being multiplied, on one hand, to the conductors of the associated connector trunk, and, on the other hand, to the contacts of the tens connector relays associated with the trunk. The relay 285 is provided in common to all the units connector relays of a trunk.

The counting relays are again operated, 120 now in accordance with the designation of the party line station desired, and operate through the agency of relays 327 and 275, one of the relays 211—214 to select the proper ringing current for signaling the desired station.

While in accordance with this preferred embodiment of the invention, counting relays are employed for controlling the selector and connector switches in accordance with the numerical impulses sent by the calling party, it will be obvious to those skilled in the art that a variety of expedients may be utilized for this purpose without departing from the spirit of the invention. Similarly, the relay switching devices herein disclosed may be replaced by devices of other types. Furthermore, the invention is applicable to operator controlled systems as well as to subscriber controlled systems.

15 DETAILED DESCRIPTION OF THE OPERATION.

Selector trunk selection.

The subscriber at station 100, desiring to obtain connection with the subscriber at station 200^a, removes his receiver from the switch-hook, whereupon the following circuit is closed: from grounded battery through the winding of line-relay 101, the lower back contact and armature of cut-off relay 102, the loop through the calling substation, and the upper armature and back contact of relay 102 to ground. The relay 101 becomes energized and closes a circuit from ground through its left-hand armature and front contact, the right-hand inner armature and back contact of slow-releasing relay 104, and the winding of relay 115 to grounded battery. The relay 115 attracts its armature, causing the establishment of the following circuits: from ground through its first (bottom) contact and the winding of slow-releasing relay 103 to grounded battery; from ground through the right-hand inner armature and front contact of the relay 101, the third contacts of relay 115, and the winding of relay 120 to grounded battery; from ground through the right-hand outer armature and front contact of the relay 101, the top contacts of relay 115, and the winding of relay 110 to grounded battery. The relays 103, 110 and 120 become energized. The relay 103 temporarily prevents the initiation of calls from the group of the calling line, and the relays 110 and 120 complete the following current paths: from ground through the second contacts of the relay 115, the winding of slow-releasing relay 104, the third contacts of relays 120 and 110, and the winding of relay 102 to grounded battery; from grounded battery through the winding of relay 106, the second contacts of relays 120 and 110, the loop through the calling substation, the top contacts of the relays 110 and 120, the winding of relay 107, and the right-hand back contact and armature of the relay 161 to ground. The relays 106, 107, 102 and 104 become energized. The relay 102 opens the circuit of the relay 101, and this in turn causes the de-energization of relay 115. The relay 106 closes an energizing circuit for slow-releasing relay 105 and relay 151. The relay 104 closes a circuit from grounded battery through its right-hand outer armature and front contact, the left-hand armature and back contact of the relay 161, and the winding of relay 162 to ground. The relay 162 becomes energized.

Upon the de-energization of the relay 115, the relay 103 becomes de-energized, but the relays 110 and 120 are maintained energized through a locking circuit including their windings and bottom contacts, and the left-hand armature and front contact of the relay 104 to ground. The relays 102 and 104 are also maintained energized, the ground removed in the second contacts of the relay 115 being substituted by a ground connection through the armature and front contact of the relay 105. The relay 162 closes a circuit from ground through the left-hand armature and front contact of relay 104, the top armature and front contact of relay 162, the armature and front contact of relay 107, the right-hand armatures and back contacts of relays 109—131 in series, and the winding of relay 108 to grounded battery. The relay 108 becomes energized and locks up through its right-hand armature and front contact and the right-hand armatures and back contacts of the relays 131'—140' in series to ground at the left-hand armature of the relay 104. The relay 151 connects ground at the armature of relay 104 through its front contact, the right-hand armature and back contact of relay 154, and the winding of relay 152 to grounded battery. The relay 152 locks up through its right-hand armature and front contact.

Hundreds selection.

The calling party proceeds now to cause the sending of a plurality of series of impulses representing the called number. Assuming that the number of the called line is 231, the calling subscriber first adjusts his calling dial to interrupt twice the line circuit. In response to each interruption of the line circuit, the relays 106 and 107 become de-energized. Relay 105 being slow to de-energize retains its armature attracted during these relatively short circuit interruptions. In response to the first release of the armatures of relays 106 and 107, relay 151 becomes de-energized and a circuit is completed from ground through the left-hand armature and front contact of the relay 104, the top armature and front contact of the relay 162, the armature and back contact of the relay 107, the left-hand inner armatures and back contacts of the relays 140'—131', the left-hand armature and front contacts of relay 108, and the winding of the relay 131 to grounded battery. The relay 131 locks up through its left-hand armature

105

110

115

120

125

130

and front contact, the left-hand armatures and back contacts of relay 132—109, and the top contacts of relay 162 to ground at the armature of relay 104. The relay 151 connects grounded battery through the winding of relay 154, the left-hand back contact and armature of relay 153, the left-hand front contact and armature of 152, and the armature and back contact of relay 151 to ground at relay 104. The relay 154 locks up through its left-hand contact. Upon the following closure of the line-circuit, the relays 106 and 107 again close their front contacts, but for an insufficient length of time to permit relay 151 to attract its armature, which is retarded by mechanical means. The ground from the armature of relay 104 is extended through the front contact and armature of relay 107, the right-hand armatures and back contacts of the relays 109—132, the right-hand armature and front contact of the relay 131, and the winding of the relay 131' to grounded battery. The relay 131' becomes energized and locks up in the same manner as relay 108. In its right-hand back contact, the relay 131' opens the locking circuit of the relay 108 and the latter becomes de-energized.

Upon the second interruption of the line circuit, the relay 107 connects ground through its back contact, the left-hand inner armatures and back contacts of the relays 140'—132', the left-hand inner armature and front contact of the relay 131', and the winding of the relay 132 to grounded battery. This relay becomes energized and locks up through the path traced for the relay 131. In its left-hand back contact, the relay 132 opens the circuit of the relay 131 and the latter becomes de-energized. The following closure of the line circuit results in the closure of a circuit for the relay 132' through the right-hand front contact and armature of the relay 132, the right-hand armatures and back contacts of the relays 133—109 in series, and the front contact of relay 107. The relay 132' becomes energized, locks up and opens the locking circuit of the relay 131'.

This last closure of the line circuit is of relatively long duration, and for this reason the slow-to-pull-up relay 151 is permitted to attract its armature. A circuit is now closed from grounded battery through the winding of relay 153, the right-hand front contact and armature of relay 154, the front contact and armature of the relay 151, and the top contacts of relay 162 to ground. The relay 153 is energized and locks up through its right-hand inner armature and front contact. Ground is now supplied through the right-hand outer armature of relay 153, the left-hand outer armature and front contact of relay 132', and the winding of relay 190 to grounded battery. The relay 190 becomes

energized and locks up through its bottom contacts, a resistance 191, and the left-hand contact of relay 104 to ground.

Connector trunk selection.

70

Assuming now that the connector trunk 171—173 is idle, the relay 201 associated with this trunk being in its normal condition, a circuit is closed from ground through the left-hand armature and back contact of the relay 204, the left-hand winding and follow-up contact of relay 201, conductor 172, the sixth or test contacts of relay 190, the armature and front contact of the relay 162, and the winding of relay 180 to grounded battery. The relay 180 becomes energized, but the current flowing through the low resistance left-hand winding of the relay 201 is not sufficient to energize the latter. The relay 180 locks up through its bottom contacts, the winding of relay 161 and the left-hand front contact of relay 104 to ground. The current flowing through this locking circuit causes the energization of relay 161, whereupon the circuit of relays 107 and 106 is interrupted in the right-hand armature and back-contact and the circuit of relay 162 is opened in the left-hand back contact of relay 161. Upon the opening of the top front contact of the relay 162, the relays 152, 153, 154, 132 and 132' are unlocked, and these relays, together with relay 151, become de-energized.

Furthermore, a circuit is closed from grounded battery through the outer armature and front contact of the relay 104, the left-hand armature and front contact of the relay 161, the fifth armature and back contact of the relay 162, the third contacts of relay 180, the back contact and armature of the relay 162, the test contacts of relay 190, conductor 172, the follow-up contacts and left-hand winding of relay 201, and the left-hand armature and back contact of the relay 204 to ground. Direct battery being connected to its winding, the relay 201 becomes energized and locks up from ground through its high resistance right-hand winding, left-hand armature and front contact and the conductor 172. A relay like 180 cannot become energized in series with such high resistance winding.

Upon the de-energization of the relay 106, the circuit of the relay 105 is opened, but before the latter has time to release its armature, a circuit is closed from grounded battery through the winding of relay 106, the contacts of relays 120 and 110 and the calling line circuit, the top contacts of the relays 180 and 190, conductor 171, and the winding of relay 202 to ground, re-energizing relay 106, and maintaining relay 105 in its actuated condition. Relay 202 is energized.

In its right-hand inner front contact and armature, the relay 201 connects ground to the left-hand armature and bank contact of

75

80

125

130

relay 204^a associated with a second connector trunk in the two hundreds group, and to the right-hand armature of relay 201^a associated with this trunk. Therefore, upon the energization of another relay like 190, instead of trunk 171—173, trunk 174—176 in the same group will be seized. The former cannot be seized on account of the high resistance path closed through the right-hand winding 5 of the relay 201, and the latter may now be seized, because the test conductor 175 is supplied with ground. As soon as the trunk 174—176 becomes busy and the relay 201^a attracts its armatures, the ground is extended 10 to the next succeeding connector trunk in the same group, etc., until the last connector trunk is reached. When the trunk 171—173 becomes idle, it may be again selected to the exclusion of all other trunks in 15 its group. The test conductors of all the connector trunks are simultaneously connected through the contacts of relay 162 to relays 180, 180^a, 180^b, etc., respectively, and the relay 180 corresponding to the first idle 20 connector trunk is actuated to extend the circuit A to this trunk. Immediate seizure of an idle trunk is made therefore regardless of the number of trunks already in use, and immediately following the seizure of this 25 trunk, the remaining trunks are released and are available for other calls.

Upon the energization of relay 202, current paths are closed from grounded battery through the winding of relay 320, the upper 30 back contacts and armatures of relays 301—310 in series, and in series through the winding of relay 320, and then through the left-hand outer back contact and armature of relay 203, the front contact and armature 35 of the relay 202, the left-hand back contact and armature of the relay 209, the right-hand back contact and armature of the relay 204, and the right-hand outer front contact and armature of the relay 201 to ground. 40 The relay 330 attracts its armatures and, somewhat later, the relay 320 attracts its 45 mechanically retarded armature. The relay 330 locks up through a circuit including its upper front contact and armature, the upper back contacts and armatures of the relays 50 301'—310', the back contact and armature of relay 340, the left-hand back contact and armature of relay 209, the right-hand back contact and armature of relay 204, and the right-hand outer front contact and armature 55 of relay 201 to ground. The relay 320 closes a circuit from grounded battery through the winding of relay 321, the upper back contacts and armatures of relays 322, 324 and 60 326 in series, the front contact and armature of relay 320, and then to ground at the armature of relay 201. The relay 321 locks up through its upper front contact and armature, the upper back contacts and armatures 65 of relays 323, 325 and 327 in series,

and then to ground at the armature of relay 201.

Tens selection.

The calling party causes now the sending 70 of the tens impulses. In the present case, assuming the tens digit to be 3, he operates the dial to cause three short circuit interruptions. The relays 106 and 202 respond to these impulses. As in the case of the 75 hundreds impulses, the relay 105 maintains its armature attracted, and the relay 320, like the relay 151, responds to the first interruptions of the circuit and releases its armature. The relay 320 does not attract its 80 armature until the termination of this series of impulses. In its back contact the relay 320 closes the energizing circuit of relay 322. A further result of the first de-energization 85 of relay 202 is the closure of a circuit from ground through the contacts of relays 201, 204 and 209, the armature and back contact of relay 202, the middle armatures and back contacts of relays 310'—301' in series, the lower armature and front contact of relay 90 330, and the winding of relay 301 to grounded battery. The relay 301 becomes energized and locks up through its lower armature and front contact and the lower armatures and back contacts of the relays 95 302—340 in series, and then to ground at the relay 201.

Upon the following short closure of the line circuit, the relays 106 and 202 are again actuated, and the latter closes a circuit from 100 ground through its armature and front contact, the left-hand outer armature and back contact of the relay 203, the winding of relay 320 the upper armatures and back contacts of the relays 310—302 in series, the 105 upper armature and front contact of relay 301, and the winding of the relay 301' to grounded battery. The relay 301' opens the circuit of relay 330 and locks up through the upper armatures and back contacts of relays 110 302'—310, and the armature and back contact of relay 340 to ground at relay 201.

In a similar manner, the second circuit interruption results in the energization of relay 302, and upon the following closure of 115 the circuit the relay 302' is operated. The relay 302 opens the locking circuit of the relay 301, and the relay 302' that of relay 301'. The third circuit interruption causes the operation of relay 303, whereupon the 120 relay 302 is unlocked.

The last relatively long circuit closure follows now. First, relay 303' is energized and causes in turn the de-energization of relay 302'. A short time thereafter, the 125 relay 320 attracts its armature and establishes a circuit from ground at the armature of relay 201, its armature and front contact, the inner armatures and back contacts of relays 326 and 324, the upper armature 130

ture and front contact of relay 322 and the winding of relay 323 to grounded battery. The relay 323 locks up and opens the locking circuit of relay 321. A circuit is now closed from ground through the contacts of relays 201, 204 and 209, the top armatures and back contacts of relays 327-324 in series, the top armature and front contact of relay 323, and the winding of relay 295 to 5 grounded battery. The desired tens connector relay is now energized over the following path: from grounded battery through the winding of #3 tens relay 290, the #3 contacts of relay 295, the lower armature and front contact of relay 303', the back contact and armature of relay 340, and then to ground at the armature of relay 201. The relay 290 locks up through its bottom contacts, a resistance 291, and the right-hand outer front contact and armature of the relay 201 to ground. At the same time, the ground applied to the third contacts of relay 295 by relay 303' is extended through the bottom contacts of 10 the relay 290, the innermost contacts of relay 295, and the winding of marginal relay 340 to grounded battery. The relay 340 becomes energized and opens in its back contact the locking circuits of the relays 303' and 303. The relay 303' removes direct ground from relay 290. This does not release relay 290 which is held up through resistance 291, but causes the de-energization of the marginal relay 340 which is 15 adjusted so that it will not hold up in series with resistance 291. The relay 303 recloses the originally traced energizing circuit of relay 330.

40 Units selection.

In accordance with the numerical designation of the units digit, which was assumed to be 1 the calling party produces now a single interruption in the line circuit. The relay 320 becomes de-energized upon the opening of its circuit in the front contact of relay 202, and closes a circuit from ground at the armature of relay 201, through its armature and back contact, the 45 lower armature and back contact of relay 325, the lower armature and front contact of relay 323, and the winding of relay 324. This relay attracts its armatures, opens the energizing circuits of relays 322 and 295 and closes a locking circuit for itself through its lower front contact and armature and the lower back contact and armature of the relay 326. The relay 301 is again operated over its above traced path 50 and locks up.

The closure of the line circuit at the calling station results in the energization and locking up of the relay 301' and the subsequent de-energization of the relay 330. 55 Shortly thereafter, the relay 320 pulls up

its armature and connects ground through its front contact, the inner armature and back contact of the relay 326, the inner front contact and armature of relay 324, and the winding of relay 325 to grounded 70 battery. Relay 325 becomes energized, unlocks relay 323 and locks up through the inner back contact and armature of relay 327. A circuit is now closed from ground at the armature of relay 201 through 75 the top armatures and back contacts of relays 327 and 326, the top armature and front contact of relay 325, and the winding of relay 285 to grounded battery. This relay becomes energized and closes a circuit from grounded battery through the winding of #1 units relay 280, the #1 contacts of relay 285, the lower front contact and armature of relay 301', the back contact and armature of relay 340, and then 80 to ground at the relay 201. The relay 280 becomes energized and closes a locking circuit for itself through its bottom contacts, resistance 281 and the armature and front contact of relay 201, and in parallel an energizing circuit for the marginal relay 340. The relay 340 opens the locking circuits of relay 301 and 301', whereupon the relay 340 becomes de-energized. The circuit of relay 330 is again established, and this 85 relay locks up.

Testing of called line.

Upon the actuation of relay 280, a test circuit is closed from ground through the 100 high resistance left-hand winding of a marginal test relay 215, the third (test) contacts of relays 280 and 290, and the winding of the called line cut-off relay 292 to battery. The relay 215 does not become energized unless full battery potential is applied to the test contacts of the connector relays, and this is the case only if no other test relay is included in a series circuit with the called line cut-off relay. Assuming that 105 the called line is idle, the relays 292 and 215 become energized. The relay 292, by attracting its armatures and thereby disconnecting line relay 293, prevents the initiation of calls by the called party, and the relay 215 closes a locking circuit for itself through its low resistance right-hand winding and the above traced test circuit. The test potential on the multiple test contacts of this called line is now reduced so 110 as to prevent the energization of another test relay upon an attempted seizure of this line. In its left-hand outer armature and front contact, the relay 215 closes an energizing circuit for relay 208 and the latter 115 attracts its armature.

Party line ringing.

Assuming now that the ringing of station "a" is desired, the calling party dials 1, 120

causing a single circuit interruption. The relay 202 is momentarily de-energized, whereupon the relay 320 releases its armature and the relay 301 becomes energized. 5 Upon the de-energization of relay 320, a circuit is closed from grounded battery through the winding of relay 326, the lower front contact and armature of relay 325, and the back contact and armature of relay 320 to ground. 10 The relay 326 opens the locking circuit of relay 324, and locks up through its lower front contact and armature. Upon the subsequent energization of relay 202, the relay 301 pulls up, opens the circuit of relay 15 330, and locks up to ground at the relay 201. The relay 320 attracts now its armature and closes an energizing circuit for relay 327 through the upper front contact and armature of the relay 326. The relay 327 20 opens the circuit of relay 325, and locks up through its middle armature and front contact.

Through its top front contact and armature, the relay 327 connects ground to the 25 winding of relay 275, and the latter becomes energized. A circuit is completed from grounded battery through the winding of relay 211, the #1 contacts of relay 275, the lower front contact and armature of relay 301', the back contact and armature of relay 340, and then to ground at the relay 201. The relay 211 becomes energized and locks up through its left-hand front contact and armature. In its right-hand inner front 30 contact and armature, the relay 211 closes an energizing circuit for relay 209 and the latter, by opening its left-hand back contact, removes the ground from the locking circuits of relays 326, 327, 320, 301 and 301'. The 35 relay 209 being energized, the relay 330 cannot be re-energized. In its left-hand armature and front contact, the relay 209 extends the ground from the relay 201, through the winding of relay 206, the left-hand inner armature and front contact of relay 215, and an interrupter 282 to grounded battery. Under the control of the interrupter, the relay 206 is intermittently energized and de-energized. While the armatures of relay 206 are 40 in their off-normal position, a circuit is closed from the 16 cycle ringing current generator through the right-hand outer armature and front contact of relay 211, the right-hand outer armature and back contact of 45 relay 207, the lower front contact and armature of relay 206, the middle armature and front contact of relay 208, the second contacts of relays 280 and 290, and the ringers at stations 200 *d* and *a* in parallel to ground. 50 Only the ringer at station 200^a is responsive to the 16 cycle current, and therefore only its bell will be rung.

When the called party removes his receiver from the switch-hook and closes a bridge 55 across the called line through the contacts of

the switchhook and dial or calling device which are represented diagrammatically on the drawing, then, upon the next silent period of interrupter 282, the relay 206 extends this bridge over its back contacts and 70 through the retardation coil 205 and the relay 204 to ground and battery. The relay 204 becomes energized and opens in its right-hand back contact the circuit of relay 211. In its left-hand front contact, the relay 204 75 closes an energizing circuit for relay 203, and this relay opens its left-hand back contact so as to prevent the re-energization of relays 320 and 330 during the restoration of the connection. Upon the de-energization 80 of relay 211, the relay 209 becomes de-energized, preventing the further operation of relay 206. The talking connection is now completed and the calling and called parties 85 may converse with each other.

It should be noted that the left-hand armature of the relay 207 is grounded, while the right-hand outer armature of this relay may be connected to the ringing generators of various frequencies through the contacts 90 of the relays 211-214. Depending on the normal or actuated condition of the relay 207, the relay 206 may thus connect ground or current source to either side of a selected line, making possible the selective ringing 95 of stations, the bells of which are grounded from opposite sides of the line or bridged across the line. If the bells are bridged across the line, the selective ringing of only four stations is possible, the desired ringing current frequency being selected by causing the operation of one of the relays 211-214. If, however, the bells are grounded from opposite sides of the line, eight stations may be arranged on a line, 100 and then their selective ringing is controlled by the mentioned relays 211-214 and the relay 207. In this case, depending on the actuated or normal condition of the relay 207, the selected ringing current generator 105 is connected to the tip or ring side of the line, all stations connected to the same side of the line being provided with differently tuned ringers.

The operation of the relay 207 is controlled by the calling party through the agency of relay 350. The winding of the relay 350 is connected to the lower armatures of the counting relays 306'-310', and the winding of relay 211 is multiplied to 115 the first and sixth contacts of the relay 275. Similarly, the winding of the relay 212 is multiplied to the second and seventh contacts of the relay 275, etc., and the winding of relay 214 is multiplied to the fourth and ninth contacts of the relay 275. For this reason, whether the subscriber sends out one impulse or six impulses, the relay 211 will 120 be energized under the control of counting relay 301' or 306'. In the latter case, how- 125 130

ever, the relay 211 is included in a series circuit with the relay 350, and this relay closes a circuit from ground through its armature and front contact and the winding of the relay 207 to grounded battery. The relay 207 is energized, locks up, and performs its above mentioned function.

The relay 350 cannot be operated during the sending of the tens or units impulses.

- 10 This is prevented by the closure of a shunt around the winding of relay 350, to the lower back contact and armature of relay 327, the left-hand back contact and armature of relay 209, the right-hand back contact and armature of relay 204, and the outer front contact and armature of relay 201 to ground. This shunt path is not opened until subsequent to the actuation of the relay 327, which occurs after the 15 sending of the party line station designating impulses.

Disconnection.

When disconnection is desired, the calling 25 and called parties restore their receivers, opening the loops closed across their lines. The relays 106 and 202 become de-energized upon the restoration of the receiver at the calling station, and the relay 204 upon the 30 hanging up of the receiver at the called station.

The relay 106 permits the de-energization of relay 105, and the latter opens the circuit of relays 104 and 102. The relay 104 35 removes the ground from the windings of relays 110, 120, 161, 180 and 190. In the right-hand outer front contact of relay 104, the battery is disconnected from the winding of relay 201, but in order to prevent the 40 seizure of the connector trunk prior to the restoration of the apparatus associated therewith, the relay 201 is maintained energized by a circuit extending from ground through its high resistance right-hand 45 winding, left-hand armature and front contact, and the left-hand inner front contact and armature of relay 203 to grounded battery.

Upon the de-energization of the relay 204, 50 the circuit of relay 203 is opened. The relay 203 causes the de-energization of the relay 201, whereupon the relays 280 and 290 are unlocked and cause the restoration of relays 292 and 215. The relay 215 opens 55 the circuit of relay 208.

If the called party restores his receiver first, then the holding of the relay 201 is insured in the following manner: Upon the hanging up of the receiver at the called station, the relay 204 is de-energized. If at this time the relay 202 is still operated, then a circuit is closed from grounded battery, through the winding, left-hand outer front contact and armature of relay 203, the 60 front contact and armature of the relay 202,

the left-hand back contact and armature of the relay 209, the right-hand back contact and armature of the relay 204, and the right-hand outer armature and back contact of the relay 201 to ground. Relay 203 is thus 70 maintained energized and holds up relay 201 through its middle armature and front contact. This condition prevails until the relay 202 becomes de-energized, whereupon 75 the connection is severed in the above described manner.

Attempted seizure of a busy line.

As above stated, if the called line is busy, the relay 215 cannot attract its armatures. 80 For this reason, the relay 208 remains in its normal condition and the talking conductors are not connected with the selected called line. When the relay 209 is operated in response to the actuation of one of the relays 85 211-214, a circuit is closed from ground through an interrupter 210, a condenser, the upper back contacts and armatures of relays 208 and 206, conductor 171, the top contacts of relays 190, 180, 120 and 110, and the receiver at the calling station. The calling subscriber will perceive a tone in his receiver indicating that the desired line is busy.

It may be desired to arrange the busy tone device so that it will start up automatically 95 when required instead of running continuously. This is accomplished by adding a contact to relays 208 and 209. Upon the energization of relay 209, if the ringing relay 208 remains de-energized by reason of the 100 fact that the wanted line is busy, a circuit is closed from ground at the outer right-hand armature of relay 201, the right-hand armature and back contact of relay 204, the middle armature and front contact of relay 209 105 and the lower armature and back contact of relay 208. The ground placed upon the start wire 220 may be utilized in the usual manner to initiate the operation of the busy tone device.

The calling party may now either hold the connection until the called line becomes idle or cause its complete restoration. In the former case, as soon as the called line becomes idle, the relay 215 attracts its armatures, and by operating relay 208, removes the tone from the calling line. In its left-hand inner front contact, the relay 215 completes the circuit of relay 206, and the called station is signaled in the same manner as 115 discussed in the previous case.

If the calling party elects to restore the connection, then by hanging up the receiver, he will cause the restoration of relays 106 and 202. The relay 106 operates in the 125 above described manner, and restores to normal all the apparatus shown in Fig. 1. The relay 203 being in its normal condition, upon the de-energization of the relay 104, the relay 201 becomes de-energized and opens the cir- 130

cuits of all the relays that were locked up through its right-hand outer armature and front contact.

What is claimed is:

6. 1. In a telephone exchange system, a line, a plurality of groups of other lines, each group bearing a different numerical designation, means for rendering busy said other lines, switching means associated with said line and operable in accordance with the numerical designations of said groups, other switching means associated with said line and operable in accordance with the busy or idle condition of said other lines, means for actuating said first mentioned switching means to select a desired group of lines, and means including said other switching means, operative thereupon for connecting said line directly to an idle one of said other lines. 70
- 10 15 20 25 30 35 40 45 50 55 60 65 70 75 80 85 90 95 100 105 110 115 120 125 130
6. 2. In a telephone exchange system, a line, a plurality of groups of other lines, each group bearing a different numerical designation, means for rendering busy said other lines, switching means associated with said line and operable in accordance with the numerical designations of said groups, other switching means associated with said line and operable in accordance with the busy or idle condition of said other lines, testing means associated with said other lines, means for actuating said first mentioned switching means to select a desired group of lines and to close the circuits of the testing means of the lines of the latter group, and means including said other switching means operative thereupon for connecting said line directly to an idle one of the lines of said group. 85
6. 3. In a telephone exchange system, a line, a plurality of groups of other lines, switching means associated with said line and provided with contacts appertaining to said other lines, means for rendering said other lines busy, testing means associated with each of said other lines, means for actuating said switching means to select a desired group of lines and close the circuits of the testing means of the lines of said group and means operative thereupon for actuating said switching means to connect the line to an idle line of said desired group. 100
6. 4. In a telephone exchange system, a plurality of lines, a plurality of groups of other lines, means for rendering busy said other lines, two groups of switching relays, means operable in accordance with numerical impulses representing said groups of other lines for actuating a certain switching relay in one of said groups, a plurality of contacts for each of the relays of said one of said groups in which lines of a group terminate, and means controlled by the condition of said other lines for actuating a switching relay of the other group. 115
6. 5. In a telephone exchange system, a plurality of lines, a plurality of groups of other lines, means for rendering busy said lines, two groups of switching relays associated with said plurality of lines, means operable in accordance with numerical impulses for actuating a certain switching relay in one of said groups, a plurality of contacts for each of the relays of said one of said groups in which lines of a group terminate, and means controlled by the condition of the lines terminating in the contacts of said certain switching relay for actuating a switching relay of the other group. 120
6. 6. In a telephone exchange system, a plurality of lines, a plurality of groups of other lines, means for rendering busy said other lines, two groups of switching relays associated with each one of said plurality of lines, a set of counting relays, means for actuating said counting relays in accordance with numerical digits representing the different groups of other lines, means operable in accordance with the actuation of the counting relays for actuating a certain switching relay in one of said groups, a plurality of contacts for each of the relays of said one of said groups in which lines of a group terminate, and means controlled by the condition of the lines terminating in the contacts of an actuated switching relay of said one of said groups for actuating a switching relay of the other group. 125
6. 7. In a telephone exchange system, a plurality of subscribers' lines, a plurality of selector trunks, a plurality of groups of connector trunks, means for rendering busy said trunks, switching relays representing tens and switching relays representing units digits of lines, means responsive to the initiation of a call for actuating a relay representing the tens and a relay representing the units designation of the calling line to connect the calling line with an idle selector trunk, two groups of switching relays and a set of counting relays associated with each selector trunk, means controlled by the calling party for actuating said counting relays in accordance with a numerical digit of the called line number, means operable in accordance with the actuation of the counting relays for actuating a certain switching relay in one of said groups, a plurality of contacts for each of the relays of said one of said groups in which connector trunks terminate, means controlled by the condition of the connector trunks for actuating a switching relay of the other group to connect the selected selector trunk with an idle connector trunk appearing in the contacts of the operated relay of said one of said groups, a set of counting relays and switching relays associated with each connector trunk representing the tens and units digits of subscribers' lines, means controlled by the calling party for operating 130

the last mentioned set of counting relays in accordance with the tens and units digits of the called number, and means operative thereupon for actuating a certain units and 5 a certain tens relay associated with the connector trunk.

8. In a telephone exchange system, a plurality of subscribers' lines, a plurality of selector trunks, a plurality of groups of connector trunks, means for rendering busy 10 said trunks, switching relays representing tens and switching relays representing units digits of lines, means responsive to the initiation of a call for actuating a relay representing the tens and a relay representing the units designation of the calling line to connect the calling line with an idle selector trunk, two groups of switching relays and a set of counting relays associated with each 15 selector trunk, means controlled by the calling party for actuating said counting relays in accordance with a numerical digit of the called line number, means operable in accordance with the actuation of the counting 20 relays for actuating a certain switching relay in one of said groups, a plurality of contacts for each of the relays of said one of said groups in which connector trunks terminate, means controlled by the condition of 25 the connector trunks for actuating a switching relay of the other group to connect the selected selector trunk with an idle connector trunk appearing in the contacts of the operated relay of said one of said groups, 30 a set of counting relays and switching relays associated with each connector trunk representing the tens and units digits of subscribers' lines, means controlled by the calling party for operating the last mentioned 35 set of counting relays in accordance with the tens and units digits of the called number, means operative thereupon for actuating a certain units and a certain tens relay associated with the connector trunk, selective 40 signaling means associated with each connector trunk, and means also operable under the control of the last mentioned counting relays for variably operating said selective signaling means. 45
9. In a telephone exchange system, a line, a plurality of variously designated groups of other lines, two switching means, means for actuating one of said switching means in accordance with the designations of said 50 groups of other lines, test circuits for the lines of a group, contacts associated with one of the lines of a group for controlling the test circuit of another line of the same group, and actuating circuits for the other switching means including said test circuits. 55
10. In a telephone exchange system, a line, a plurality of variously designated groups of lines, two groups of relays associated with said line, means for operating the relays of one group in accordance with the 60
- 65

designation of the groups of lines, a test circuit for each one of said other lines, contacts associated with said other lines included in the test circuits of lines belonging to the same group, and actuating circuits 70 for the relays of the other group including said test circuits and contacts of the relays of the said one of said groups.

11. In a telephone exchange system, a line, a plurality of groups of other lines, means 75 for rendering said other lines busy, test circuits associated with each of said other lines, switching means associated with the first mentioned line and responsive to the busy or idle condition of the other lines, 80 and means for closing simultaneously all of the test circuits of the lines of one of said groups and the actuating circuits of said switching means. 85

12. In a telephone exchange system, a line, 85 a group of other lines, means for rendering said other lines busy, test circuits, a test relay individual to said first line and provided with contacts in said test circuits, a plurality of other relays provided with contacts 90 appertaining to said first line, and means for actuating said test relay to close said test circuits and the actuating circuit of a certain one of said other relays, whereby the first mentioned line is connected to an idle one 95 of the lines of said group.

13. In a telephone exchange system, a line, a plurality of groups of other lines, means for rendering said other lines busy, test circuits associated with each of said other lines, 100 a test relay individual to said first line and provided with contacts in said test circuits, a plurality of relays provided with contacts appertaining to said first line, a plurality of 105 relays provided with contacts in which the lines and test circuits of said groups terminate, means for actuating one of the latter relays to select a certain one of said groups, and means for actuating the test relay to 110 close the test circuits of said group and the actuating circuit of a certain one of the first mentioned plurality of relays, whereby the first mentioned line is connected to an idle one 115 of the lines of a desired group.

14. In a telephone exchange system, a line, a group of other lines, means for rendering said other lines busy, a plurality of relays provided with contacts in which the multiplied terminals of said first mentioned line terminate, testing means associated with said other lines, actuating circuits for said relays including said testing means, a relay provided with contacts in which the lines of said group terminate and also provided with contacts in said circuits, means for actuating the latter relay, and means including said testing means and actuating circuits for thereupon actuating one of said plurality of relays to connect said first mentioned line 120 to an idle one of said other lines. 125

130

15. In a telephone exchange system, a line, a plurality of groups of other lines, means for rendering said other lines busy, testing means associated with said other lines, a plurality of relays provided with contacts in which the said groups of lines terminate and other contacts which are in the circuits of said testing means, a relay individual to said first mentioned line provided with contacts in the circuits of said testing means, ¹⁰ means for actuating one of said plurality of relays to select a desired group of lines, and means including said testing means and said relay for connecting said line to an idle one of the lines of said group. ¹⁵

In witness whereof, I hereunto subscribe my name this 1st day of June, A. D. 1920.

ROY C. ARTER.
